ELECTRIC CIRCUIT CONTROLLER

George R. Townsend, Schenectady, and Chester I. Hall, Vischer's Ferry, N. Y., assignors to General Electric Company, a corporation of New York

Application February 17, 1943, Serial No. 476,202

7 Claims. (Cl. 200—116)

Our invention relates to electric circuit controllers, and more particularly to thermal responsive electric switches of the general type disclosed in Patent 1,527,645—Hall for effecting the interruption of an electric circuit in response to a sustained abnormal current.

It is a general object of our invention to produce a new and improved thermal overload switch of the above character which shall be of simple and rugged construction, inexpensive to manufacture, and durable, reliable and accurate in operation.

It is a further object of our invention to provide a new and improved thermal overload relay which shall be insensitive to vibration and to severe impact.

It is a still further object of our invention to provide a new and improved means for accurately calibrating an electric circuit controller of the thermal latch type.

It is a specific object of our invention to provide calibrating means particularly adapted for the precise calibration of a thermal overload relay of the shock-proof type.

In carrying out our invention in one form, we provide a pair of cooperating switch contacts arranged either directly or indirectly to control the current in an electric circuit to be protected. To effect suitable controlling movement of the contacts in response to an abnormal current in the circuit, we provide a thermally expansible element fixedly mounted at one end and connected at its other end to a pivoted detent lever. The detent lever is connected for continuous following engagement with the movable end of the thermal member by providing little, or substantially no, lost motion in the connection therebetween. A switch actuating member is arranged normally to be held in a latched position by the detent lever and is pivotally mounted upon a double eccentric pivot having a multiplicity of adjustments for controlling the position of the switch actuating member in its latched position with respect to the detent lever. By movement of the latched member relative to the detent lever, it is possible to determine the position of the latch lever, and hence the temperature of the thermal responsive member, at which release of the switch actuating member is effected.

Our invention itself will be more fully understood by referring now to the following detailed specification taken in conjunction with the accompanying drawing in which Fig. 1 is a front view of a thermal overload relay embodying my invention; Fig. 2 is a cross-sectional view of the

relay of Fig. 1 taken along the line 2—2 of Fig. 1; Fig. 3 is a front view similar to Fig. 1 showing one of the thermal responsive assemblies in its tripped position; and Fig. 4 is an exploded perspective view of the doubly adjustable pivot means for the switch actuating member.

Referring now to the drawing, we have shown a preferred embodiment of our invention in the form of a thermal responsive electric switch suitable for the protection of a three-phase electric circuit in the manner described in connection with Fig. 3 of the above-identified patent to Hall. The relay comprises a pair of thermal responsive assemblies 10 and 11 mounted within an insulating casing 12 for joint cooperation with a pair of cantilever spring contacts 13 and 14 which are connected respectively to a pair of switch terminals 13a and 14a upon the top of the casing 12. The switch contacts 13 and 14 are biased into engagement. The thermal assembly 10 is arranged to actuate the switch contact 14 to a circuit interrupting position and the thermal assembly 11 is arranged to actuate the switch contact 13 to a circuit interrupting position. The thermal assemblies are disposed in juxtaposition on opposite sides of the casing 12 for joint cooperation with the contacts 13 and 14 in the manner described. Since the assemblies 10 and 11 are of similar construction, only one will be described in detail.

Referring now more particularly to the thermal assembly 10, this unit comprises a box-like base 15 attached to the back of the casing 12 by bolts 16 and 17 and having an upper end wall 18 for supporting a hollow tube 19 of thermally expansible material, such as nickel or a special alloy having a high coefficient of expansion. The base 15 is also provided with a side and front wall 20 partially enclosing the tube 19. The thermally expansible tube 19 is arranged to be heated by a hairpin shaped heater 21 extending through the top of the casing 12 into the tube 19 and having its ends connected to a pair of heater terminals 22 and 23 mounted externally of the casing 12.

At the lower end of the base plate 15 a detent lever 24 is pivotally mounted upon a pin 25 extending between the front and rear walls of the base plate 15. The detent lever 24 is connected intermediate its ends to the lower or movable end of the thermally expansible tube 19. In the form of the invention shown in the drawing, the connection of the tube 19 to the detent lever 24 is made by cutting away one-half of the periphery of the tube for a portion of its length at the

lower end and slotting the remaining half of the tube 19, the detent lever 24 passing through the slot in the tube. Preferably, the length of the slot in the lower end of the tube 19 is sufficient to permit insertion of the lever 24 and a torsion spring (not shown) encircling the pivot pin 25 biases the lever 24 into continuous following engagement with the lower edge of the slot so that there is substantially no lost motion between the detent lever and the expansible tube.

For actuating the switch contact 14 in response to the movement of the detent lever 24, we provide a switch actuating member 26 pivotally mounted upon an adjustable sleeve 27 and biased by means of a torsion spring 28 for counterclockwise rotation into engagement with the switch contact 14. The switch actuating member 26 is provided with a striker arm 29 positioned to engage the contact 14 for moving the contact to its open circuit position. A reset arm 30 is also mounted upon the actuating member 26 for moving the actuating member from its released or switch opening position back to its latched position. Preferably, both arms 29 and 30 are formed of insulating material. The lower end of the switch actuating member 26 carries a pivotally mounted movable latch 31 which is rotatable through a small angle in a counterclockwise direction with respect to the switch actuating member 26 to permit resetting of the switch actuating member in its latched position behind a latching dog 32 at the end of the detent lever 24.

The switch actuating member 26 is pivotally mounted upon the base plate 15 through a double eccentric pivot arrangement permitting a vernier adjustment of the switch actuating member with respect to the detent lever 24. The adjustable pivot for the member 26 is illustrated in detail in the perspective view of Fig. 4. This mounting comprises an adjustable plate or lever 35 having extending from one side thereof a fixed pivot pin 36 for cooperation with a suitable bore in the base plate 15 pivotally to mount the adjustable plate 35 upon the base plate. The lower end of the plate 35 is slotted radially, as at 37, for cooperation with a clamping bolt 38 in the plate 15 adjustably to fasten the plate 35 to the base 15 in a desired fixed position. Upon the front surface of adjustable plate 35 there is mounted eccentrically with respect to the pivot pin 36 an adjustable pivot pin 39. The adjustable sleeve 27 is eccentrically bored and rotatably mounted upon the adjustable eccentric pivot pin 39. For adjustably flexing the position of the sleeve 27 with respect to the base 15 and thus with respect to any desired fixed position of the pivot pin 39 an adjusting arm 41 is connected to the sleeve 27. As illustrated at Fig. 1, the adjusting arm 41 is slotted radially as at 42 for cooperation with a clamping bolt 43 mounted in the front wall 20 of the base 15 thereby adjustably to fasten the sleeve 27 in any desired position. The sleeve 27 serves as a pivot pin for the switch actuating member 26. It will now be observed that, while the center of the sleeve 27 serves as the pivot point for the member 26, the position of this pivot point with respect to the base plate 15 may be controlled over a wide range by the adjustable plate 35 and over a smaller range within the setting of the plate 35 by means of the eccentric sleeve 27.

Since the detent lever 24 is held in continuous following engagement with the lower end of the thermally expansible tube 19, it will be evident

that the position of the latching dog 32 is determined directly by the temperature of the tube 19. Thus, by adjusting the position of the switch actuating lever 26 with respect to the detent lever

- 5 24 and dog 32, the thermal responsive unit may be calibrated for release of the switch actuating member at any desired temperature of the thermally expansible tube 19. An approximate setting may be attained by adjustment of the plate 10 35, and thereafter a fine vernier adjustment may be effected through proper setting of the eccentric sleeve 27 by means of the attached lever 41. If desired, the plate 35 may be used as a 15 factory adjustment and its position fixed after proper setting, while the lever 41 may be left available to the customer for refinement of the factory setting. For this purpose the lever 41 is conveniently positioned at the front of the casing.
- 20 In view of the foregoing detailed description of the various parts of our thermal relay and the manner of their assembly, it is believed that the mode of operation of the device as a whole will be evident without detailed explanation. Briefly, 25 however, a sustained flow of excessive current through the heater 21 will raise the temperature of the thermally expansible tube 19, thereby causing the tube 19 to expand longitudinally and to move its lower end downward with respect to 30 the base plate 15. Such movement of the lower end of the tube 19 permits a clockwise rotation of the detent lever 24 which, if sufficient, releases the latch 31 and permits the switch actuating lever 26 to rotate in a counterclockwise direction 35 under the influence of its biasing spring 28. Movement of the switch actuating lever 26 to its released position brings the striker arm 29 into engagement with the spring contact 14 thereby to move the contact 14 to a circuit interrupting position, as illustrated at Fig. 3. In 40 moving to its released position, the switch actuating member 26 also raises one end of the reset lever 30. The raised end of the lever 30 is arranged to be engaged by a manually operable 45 reset push button 45. The push button 45 is normally biased to a non-operative position by means of a helical compression spring 46, but may be depressed manually to engage the reset lever 30 and to rotate the switch actuating lever 50 26 in a clockwise direction to the latched position shown at Fig. 1.

While we have shown only a preferred embodiment of our invention by way of illustration, many other modifications will occur to those skilled in the art, and we therefore wish to have it understood that we intend in the appended claims to cover all such modifications as fall within the true spirit and scope of our invention.

What we claim as new and desire to secure by Letters Patent of the United States is:

- 60 1. An electric circuit controlling apparatus comprising a pair of cooperating switch contacts, a switch actuating member biased for movement to a released position to effect circuit controlling movement of said contacts, a movable detent member for normally releasably retaining said switch actuating member in a latched position against its bias, and means for adjusting the latched position of said switch actuating member 65 with respect to said detent member comprising a laterally adjustable pivot pin and adjustable means rotatably mounted upon said adjustable pivot pin for pivotally supporting said switch actuating member.
- 70 2. An electric circuit controlling apparatus

comprising a pair of cooperating switch contacts, a switch actuating member biased for movement to a released position to effect circuit controlling movement of said contacts, a detent member arranged normally releasably to retain said switch actuating member in a latched position against its bias, thermal responsive means for moving said detent member in accordance with the temperature of said thermal responsive means to release said switch actuating member, and means for adjusting the latched position of said switch actuating member with respect to said detent member thereby to set said switch actuating member for release at a predetermined temperature of said thermal responsive means comprising an adjustable pivot pin, an adjustable member eccentrically and pivotally mounted upon said pivot pin, and means for pivotally mounting said switch actuating member upon said adjustable member.

3. An electric circuit controlling apparatus comprising a pair of cooperating switch contacts, a switch actuating member biased for movement to a released position to effect circuit controlling movement of said contacts, a movable detent member for normally releasably retaining said switch actuating member in a latched position against its bias, and means for adjusting the latched position of said switch actuating member with respect to said detent member comprising an adjustable pivot pin, an adjustable sleeve eccentrically and rotatably mounted upon said adjustable pivot pin, and means for pivotally mounting said switch actuating member upon said adjustable sleeve.

4. An electric switching apparatus for controlling an electric circuit comprising a pair of cooperating switch contacts, a switch actuating member biased for movement to a released position to effect circuit controlling movement of said contacts, a detent member for normally releasably retaining said switch actuating member in a latched position against its bias, a thermally responsive member arranged to move said detent member in accordance with the magnitude of current in said circuit, said detent member being connected for continuous following engagement with said thermally responsive member, and means for adjusting the latched position of said switch actuating member with respect to said detent member thereby to determine the current value at which said switch actuating member is released by said detent comprising an adjustable plate pivotally mounted at a fixed point, a pivot pin eccentrically mounted upon said adjustable plate, an eccentric sleeve rotatably mounted upon said pivot pin, means for pivotally mounting said switch actuating member upon said eccentric sleeve, and means for adjustably positioning said sleeve with respect to said pivot pin.

5. A shock-proof electric switching apparatus for controlling an electric circuit comprising a base, a pair of cooperating switch contacts, a switch actuating member biased for movement to a released position to effect circuit controlling

5 movement of said contacts, a detent member for normally releasably retaining said switch actuating member in a latched position against its bias, a thermally expandable member fixedly mounted at one end upon said base, means for connecting said detent member for continuous following engagement with the movable end of said thermally expandable member, and means for adjusting the latched position of said switch actuating member with respect to said detent member thereby to determine the temperature of said thermally expandable member at which release of said switch actuating member is effected comprising a movable plate pivotally mounted and adjustably positionable upon said base, a pivot pin eccentrically mounted upon said movable plate, an eccentric sleeve rotatably mounted upon said pivot pin, means for pivotally mounting said switch actuating member upon said eccentric sleeve, means for adjustably positioning said eccentric sleeve upon said pivot pin, and means for connecting said sleeve to said base in a desired position of adjustment.

6. An electric circuit controlling apparatus comprising a base, a pair of cooperating switch contacts, a switch actuating member biased for movement to a released position to effect circuit controlling movement of said contacts, a movable detent member for normally releasably retaining said switch actuating member in a latched position against its bias, means for movably mounting one of said members for predetermined movement with respect to said base, and means for relatively adjustably positioning said switch actuating and detent members in their latched positions comprising an adjustable pivot pin mounted upon said base for lateral movement with respect thereto and adjustable means rotatably mounted upon said adjustable pivot pin for pivotally supporting the other of said members.

7. An electric circuit controlling apparatus comprising a base, a pair of cooperating switch contacts, a switch actuating member biased for movement to a released position to effect circuit controlling movement of said contacts, a detent member arranged normally releasably to retain said switch actuating member in a latched position against its bias, thermal responsive means for moving said detent member in continuous following relation with respect to a thermally movable portion of said thermal responsive means, means for movably mounting one of said members for predetermined limited movement with respect to said base, and means for relatively adjustably positioning said switch actuating and detent members in their latched positions comprising an adjustable pivot pin movably mounted upon said base, an adjustable sleeve eccentrically and rotatably mounted upon said adjustable pivot pin, and means for pivotally mounting the other of said members upon said adjustable sleeve.

GEORGE R. TOWNSEND.
